(57) **CLAIM**

The ornamental design for a computer mouse with bullet shape, as shown.

DESCRIPTION

FIG. 1 is a top perspective view of a computer mouse with bullet shape showing our new design; the broken lines are for illustrative purposes only and form no part of the claimed design;

FIG. 2 is a top plan view thereof;

FIG. 3 is a rear elevation view thereof;

FIG. 4 is a left side elevation view thereof;

FIG. 5 is a right side elevation view thereof;

FIG. 6 is a front elevation view thereof; and,

FIG. 7 is a bottom plan view thereof.
